UNITED STATES PATENT OFFICE.

JOSEPH V. MCADAMS, OF TABLEROCK, WYOMING.

FLASH-CANDLE.

1,268,589.

Specification of Letters Patent. Patented June 4, 1918.

Application filed October 24, 1917. Serial No. 198,350.

To all whom it may concern:

Be it known that I, JOSEPH V. MCADAMS, a citizen of the United States, residing at Tablerock, in the county of Carbon and State of Wyoming, have invented certain new and useful Improvements in Flash-Candles; and I do hereby declare the following to be a full, clear, and exact description of the invention, such as will enable others skilled in the art to which it appertains to make and use the same.

My invention relates to flash candles and more particularly to the construction, and use of such candles as scarecrows for coyotes. It has for an object the production of a simple, economical, inexpensive, and reliable means for alarming prowling animals during the nightime, being designed, adapted, and primarily intended for guarding sheep in flocks and protecting them from attacks of wild beasts, more especially coyotes so numerous in some sheep-raising sections.

Heretofore the most effective preventive employed by sheep raisers has been bulk sulfur mixed with blasting or other powder, in cans or other receptacles. It is a well known fact that coyotes are quite wary of the smell of sulfur, and even more so of the flash when it is ignited. By this method it is also a noticeable fact that ashes accumulate as the sulfur burns, thus oftentimes smothering the flame, moreover, windy weather extinguishes the same, oftentimes capsizing the receptacle, and rain water floods the can, thus rendering its contents ineffective. These and similar objections to the heretofore general use of bulk sulfur as aforesaid are well recognized, and to overcome such objections is also an object of the present invention.

With these and other objects in view the invention will now be particularly described, and then pointed out by the claims following.

In the accompanying drawings which form part of this application for Letters Patent, and whereon corresponding reference numerals indicate like parts in the several views:

Figure 1 is a side elevation of my invention complete and ready for use.

Fig. 2 is a similar view upon a slightly enlarged scale, of one candle having its oiled paper wrapper broken away, and itself

broken out longitudinally exposing to view the hanger or support for the device, and

Fig. 3 is a transverse sectional view taken through one of the powder charges.

Reference being had to the drawings and numerals thereon, 5 indicates the core or body of the device being formed of sulfur mixed with cotton, which consequently is slow burning. At regular intervals throughout the length of the candle there are provided charges of powder 6, which may be radially arranged from center to circumference of the structure as shown by Fig. 3, or introduced in any other approved form and quantities.

Traversing one side of the core or body 5 of the structure is a hanger rod, or strip of metal 7 having a hooked upper end 8 to facilitate hanging same upon a suitable support when in service. Surrounding and enveloping the several elements aforesaid is an outer cover or sheath of oiled paper 9, which serves to protect the candle from the disastrous effects of rain water, as also to retain the hanger 7 in place.

The foregoing being a general description of my invention, in one approved embodiment, its use may be briefly set forth as follows:

Supported upon stakes or other supports in circular arrangement, for example around a flock of sheep at night, the entire series of candles is successively lighted at intervals of about five minutes. They then smolder and burn slowly, emitting a strong sulfurous odor until the first fuse or charge 6 is reached in the candle first lighted, whereupon the same flashes for the purpose of alarming lurking beasts of prey. By preference the succeeding charges or fuses 6 of each candle are so positioned that each succeeding charge is fired and flashed at intervals of about twenty-five minutes, and as a result of this timing, the circular arrangement of similar candles, and the intervals at which they are originally lighted, it is obvious that a continuous circular intermittent firing or flashing will be effected, and this has been found to be productive of the most satisfactory results.

Moreover, it is entirely within the spirit of this invention to vary the timing and the duration of flashes indefinitely, as also to use fuses 6 which produce various colored lights when burning, and it will be particu-

larly noted that the burnt ashes simply fall from the candle to the ground without in the least interfering with the functions of the device.

5 Having thus described my invention in one form of construction, what I now claim and desire to secure by Letters Patent is:

1. In a slow burning candle, the combination with an outer sheath of a supporting member extending through the length of said candle between the said outer sheath and the body of the candle.

10 2. In a slow burning candle composed of cotton and sulfur, the combination with flash fuses arranged therein at predetermined intervals, of a suitable supporting hanger, and an outer sheath enveloping said candle and the body of said hanger.

15 3. In a slow burning candle composed of cotton and sulfur, the combination with flash charges embedded therein at intervals, of a suitable hanger, and an outer sheath of

oiled paper enveloping said supporting hanger and candle throughout the length of the candle.

25 4. In a slow burning candle the combination with flash charges entering said candle radially at predetermined intervals, of a suitable hanger connected to said candle by a surrounding inflammable envelop.

30 5. In a slow burning candle the combination with an outer sheath of a supporting member, said supporting member being secured between the body of the candle and the outer sheath, and having oppositely arranged hooked ends, one of which engages the lowermost edge of the outer sheath.

In testimony whereof I affix my signature, in presence of two subscribing witnesses.

JOSEPH V. McADAMS.
